UNITED STATES PATENT OFFICE

JOHN A. BELL, OF LOS ANGELES, CALIFORNIA, ASSIGNOR TO RAILWAY SPECIALTIES COMPANY, OF LOS ANGELES, CALIFORNIA, A CORPORATION OF CALIFORNIA.

DESIGN FOR A WIGWAG FLAGMAN.

45,784.

Specification for Design.

Patented May 19, 1914.

Application filed February 3, 1914. Serial No. 816,367. Term of patent 14 years.

To all whom it may concern:

Be it known that I, JOHN A. BELL, a citizen of the United States, residing at Los Angeles, in the county of Los Angeles and State of California, have invented a new, original, and ornamental Design for a Wig-wag Flagman, of which the following is a specification, reference being had to the accompanying drawing, forming a part thereof.

Figure 1 is a front elevation of a wig-

wag flagman, showing my new design. Fig. 2 is a side elevation of the design.

I claim:

The ornamental design for a wig-wag flagman, as shown.

JOHN A. BELL.

Witnesses:

LORRAINE E. DURROW,
G. F. HACKLEY.
